(57) **CLAIM**

The ornamental design for a wearable accessory for holding gear, as shown and described.

DESCRIPTION

FIG. 1 is a front, top, and right side perspective view of a wearable accessory for holding gear in an opened position showing my new design;

FIG. 2 is a front, top, and left side perspective view thereof; FIG. 3 is a front, bottom, and right side perspective view thereof;

FIG. 4 is a front, bottom, and left side perspective view thereof;

FIG. 5 is an elevational front view thereof;

FIG. 6 is an elevational left side view thereof;

FIG. 7 is an elevational rear view thereof;

FIG. 8 is an elevational right side view thereof;

FIG. 9 is an elevational top view thereof;

FIG. 10 is an elevational bottom view thereof;

FIG. 11 is a front, top, and right side perspective view of the wearable accessory for holding gear in a closed position, showing my new design;

FIG. 12 is a front, top, and left side perspective view thereof; FIG. 13 is a front, bottom, and right side perspective view thereof;

FIG. 14 is a front, bottom, and left side perspective view thereof;

FIG. 15 is an elevational front view thereof;

FIG. 16 is an elevational rear view thereof;

FIG. 17 is an elevational right side view thereof;

FIG. 18 is an elevational left side view thereof;

FIG. 19 is an elevational top view thereof; and,

FIG. 20 is an elevational bottom view thereof.

Broken lines on the article depict stitching and are part of the claimed design.
